Primary Examiner — Darlington Ly(74) *Attorney, Agent, or Firm* — Davis Wright Tremaine LLP; Heather M. Colburn(57) **CLAIM**

The ornamental design for a reverse trike vehicle, as shown and described.

DESCRIPTION

FIG. 1 is a rear perspective view of a reverse trike vehicle showing our new design;

FIG. 2 is a front perspective view thereof;

FIG. 3 is a right side elevational view thereof;

FIG. 4 is a left side elevational view thereof;

FIG. 5 is a front elevational view thereof;

FIG. 6 is a rear elevational view thereof; and,

FIG. 7 is a top plan view thereof.

The broken lines in the drawings illustrate portions of the reverse trike vehicle that do not form part of the claimed design.

1 Claim, 7 Drawing Sheets(56)
